(57) **CLAIM**

The ornamental design for an electrical cord connection protector, as shown and described.

DESCRIPTION

FIG. 1 is a front elevated view of an electrical cord connection protector showing my new design.

FIG. 2 is a back elevated view of the electrical cord connection protector.

FIG. 3 is a side elevated of the electrical cord connection protector.

FIG. 4 is a top view of the electrical cord connection protector.

FIG. 5 is a bottom view of the electrical cord connection protector; and,

FIG. 6 is a perspective view of the electrical cord connection protector.

The broken line environmental showing is for illustrative purposes only and forms no part of the claimed design.
